Primary Examiner—Philip S Hyder*Assistant Examiner*—Susan E Krakower*(74) Attorney, Agent, or Firm*—Nelson Mullins Riley & Scarborough, LLP(57) **CLAIM**

The ornamental design for a dynamic splint assembly, substantially as shown and described.

DESCRIPTION

FIG. 1 is a left side view of a dynamic splint assembly showing the design of the present invention;

FIG. 2 is a right side view of the dynamic splint assembly illustrated in FIG. 1;

FIG. 3 is a front perspective view of the dynamic splint assembly illustrated in FIG. 1;

FIG. 4 is a rear perspective view of the dynamic splint assembly illustrated in FIG. 1; and,

FIG. 5 is a top view of the dynamic splint assembly illustrated in FIG. 1.
